UNITED STATES PATENT OFFICE.

FREDERICK MUELLER, OF IRVINGTON, NEW JERSEY.

PISTON OR COMPRESSION RING.

1,414,747.

Specification of Letters Patent. Patented May 2, 1922.

Application filed March 20, 1919. Serial No. 283,847.

To all whom it may concern:

Be it known that I, FREDERICK MUELLER, a citizen of the United States, residing at Irvington, in the county of Essex and State 5 of New Jersey, have invented certain new and useful Improvements in Piston or Compression Rings; and I do hereby declare the following to be a full, clear, and exact description of the invention, such as will enable others skilled in the art to which it 10 appertains to make and use the same, reference being had to the accompanying drawings, and to characters of reference marked thereon, which form a part of this specification.

15 This invention relates, generally, to improvements in piston-rings; and, the present invention has reference, more particularly, to a novel construction of piston-ring adapted for use with engines of the various kinds, 20 and especially with internal explosive or combustion engines, such as are used with automobiles.

25 My present invention, therefore, has for its principal object to provide a novel and simply constructed piston-ring of the general character hereinafter set forth, with a view of providing a piston-ring which can be readily slipped over the end of the piston, without straining or distorting the perfect 30 annulus and outer fitting surface of the ring, the ring thus being adapted to maintain at all times a snug and evenly wearing connection between the piston and cylinder-wall.

35 Because of the shape of the interior surface of the annulus, providing practically a re-inforced ring although made in one piece, the ring will not be strained or will not break in placing it in position upon the piston, will produce a perfect fit throughout its 40 outer contacting surface- portions, thus economizing in the consumption of the explosive fuel, and at the same time will prevent the contacting surface of the ring from becoming pitted or set with carbon.

45 Other objects of the present invention not at this time more particularly enumerated will be clearly understood from the following detailed description of the present invention.

50 With the above-stated objects in view, the present invention consists, primarily, in the novel piston-ring of the general character and construction hereinafter more fully set forth.

The invention is clearly illustrated in the 55 accompanying drawings, in which:—

Figure 1 is a plan view of a completed piston-ring made according to and embodying the principles of the present invention; Figure 2 is an elevation of the same; and 60 Figure 3 is a transverse vertical section of said piston-ring.

Figure 4 is an enlarged detail vertical section of a portion of the said ring, said view illustrating more clearly, one manner of providing the interior surface of the ring with a multiplicity of alternating annular ribs or raised portions and annular grooves or depressed portions.

Figure 5 is a vertical sectional representation of a piece of tubing, illustrating the various steps of the method for producing the piston-rings according to the principles of the present invention.

Similar characters of reference are employed in the said above described views, to indicate corresponding parts.

Referring now more particularly to Figures 1, 2, 3 and 4 of the drawings, the reference-numeral 1 indicates the complete piston-ring, the ring in the present case consisting of a single annulus, having a joint formed by the two interlocking projecting end-portions or tongues 2 and 3, as shown in Figure 2 of the drawings. In practice, I prefer to make 85 the interlocking projecting end-portions at their respective abutting surface- portions, when the ring is entirely closed, with convexly-formed and concavely-formed corner-portions, as 4 and 5, adapted to be brought 90 into registration with each other, as shown in said Figure 2, whereby the danger of the breaking away or cracking of the said tongues due to crystallization or otherwise, as is so often the case where sharp corners 95 are employed, is substantially overcome. As shown more particularly in the drawings, the outer surface-portion 6 of the ring is a true cylinder, or when viewed as shown in Figure 1, a true circle. The opposite sides or planes 100 7 and 8 of the annulus are straight, and the inner surface of the annulus, intermediate of the said straight sides or planes 7 and 8 is made up of a multiplicity of alternately disposed annular raised members 9 and annular grooves or depressions 10, the raised members being convex in cross-section and the grooves or depressions being concave in

cross-section, as will be clearly evident from an inspection of Figures 3 and 4 of the drawings.

Having in the foregoing described the 5 general construction of piston-ring made according to the principles of the present invention, I will now briefly set forth the preferred method of producing the same.

Referring now to Figure 5 of the drawings, the reference-character 11 indicates a suitable length of tubing, preferably provided at one end with a flange, as 12, for securing the same in position at said end of the tubing to the head or chuck of a lathe.

15 The normal thickness of the wall-portions of this tubing is indicated by the longitudinally extending dotted lines 13—13 in said Figure 5. By means of the proper cutting tool, the inner surface of the said tubing 20 is cut away so as to provide said surface with a multiplicity of alternating annular ribs or raised portions 14 and annular grooves or depressions 15 corresponding in 25 configuration to the above-mentioned annular ribs or raised portions 9 and annular grooves or depressions 10.

After these ribs or raised portions 14 and grooves or depressions 15 have been formed within the tubing, these parts are highly 30 polished, and then a rolling tool is inserted in the grooves, and with the proper application of pressure, the channelled portions between the ribs are rolled out, thereby providing an inner surface of greater density 35 than the outer surface-portions of the tubing for the purposes to be presently more fully stated.

Parallel rings of suitable width are thereupon sawed or cut by means of a parting 40 tool on the dotted lines 16—16 from the tubing. Any suitable number of such rings are next placed upon an arbor which is secured in a lathe, and the outer cylindrical surfaces of the assembled ring then turned 45 down so as to provide a perfectly smooth and uniform cylindrical surface to provide rings of the desired size. This turned down surface is next carefully polished, and the rings are thereupon removed from the arbor. 50 Each ring is next placed in a milling ma-

chine and by means of the proper milling tool the ring is milled across its width to provide a split ring having previously mentioned interlocking end-portions or tongues 2 and 3.

55 After the split ring has been, in the above manner, finally completed, owing to the inner rounded marginal edge-portions it can be easily slipped over the end of the piston, and sprung into its packing position in the 60 usual annular groove with which the piston is provided.

The above-stated rolling operation has produced the ring with great resilient properties, so that the ring accurately engages the inner wall of the cylinder peripherally at all points. The perfect cylindrical contact insures a uniform wear of the ring at all points, so that perfect compression is the constant result, any leakage 65 of the motive fluid from the one end of the piston in that portion of the cylinder in which it is required to the opposite end of the piston being obviated.

70 I claim:—

75 1. A piston-ring comprising a single split annulus having a true outer cylindrical and smooth contacting surface and straight sides, the inner annular surface-portion being provided with a series of annular ribs 80 of convex cross-section and an intermediate annular depression throughout of greater density than said contacting surface.

2. A piston-ring comprising a single split annulus having a true outer cylindrical and 85 smooth contacting surface and straight sides, the inner annular surface-portion being provided with a multiplicity of alternating annular ribs of convex cross-section and annular depressions of concave cross-section 90 throughout of greater density than said contacting surface.

In testimony that I claim the invention set forth above I have hereunto set my hand this 17th day of March, 1919.

FREDERICK MUELLER.
